SAFETY AUTOMATIC DOOR STOP

James J. Reid and James F. Brown, Philadelphia, Pa.

Application March 23, 1953, Serial No. 344,258

10 Claims. (Cl. 20—16)

(Granted under Title 35, U. S. Code (1952), sec. 266)

The invention described herein may be manufactured and used by or for the Government of the United States of America for governmental purposes without the payment of any royalties thereon or therefor.

The present invention relates to a latching device or the like and more particularly to a novel and improved automatic safety latch device which is simple in construction and reliable in use.

The invention is primarily intended for use with the large type of pull-up doors which are oftentimes used to close relatively large entrances of buildings such as vehicle entrances and the like. These large doors usually also contain one or more smaller doors through which personnel may conveniently pass. Although the small doors are ordinarily provided with a conventional type of door latch, the same frequently become unlatched while the large door is in its raised open position. In doing so they are then capable of swinging downwardly on their hinges with considerable force thereby endangering the safety of persons working and/or passing therebelow.

The principal object of the present invention is to provide a novel and improved device for automatically locking the smaller door in its closed condition as soon as the larger door begins to move upwardly towards its elevated overhead position.

Other objects and many of the attendant advantages of this invention will be readily appreciated as the same becomes better understood by reference to the following detailed description when considered in connection with the accompanying drawings wherein:

Figure 1 is a front elevational view of a large pull-up type of door having a smaller personnel door positioned therein and the improved safety latch of the present invention mounted thereon;

Figure 2 is an enlarged view of one embodiment of the improved safety latch shown in Figure 1; and

Figure 3 is an enlarged view of a modified embodiment of the safety latch shown in Figure 1.

In general, the improved device for latching the small door in a large overhead type door in its closed position includes a first member which is positioned on the large door and which is adapted to retractably extend downwardly beyond the lower extremity thereof; a second member which is also positioned on the large door and which is adapted to retractably extend upwardly beyond the lower extremity of the small door; and means operatively connected to the first and the second members for simultaneously moving the same between their extended and retracted positions. It has been found that such a device though relatively simple in construction provides a reliable and effective safety latch.

One preferred embodiment of the present invention is shown in Figures 1 and 2 of the drawing. As illustrated therein, the enlarged vehicle entrance or the like in the building 3 is provided with a conventional overhead type door 4 which as is customary in the art is preferably divided into the horizontally hinged sections 4a and

4b. Although the particular arrangement whereby the door 4 is operated between its open and closed positions could take a variety of different forms, a full description of the same is not considered expedient herein since it forms no part of the present invention. It need merely be understood for a complete understanding of the present invention that the door 4 moves in any suitable manner from a closed position (where its bottom edge 4c engages the floor of the building) upwardly and then inwardly toward its overhead or elevated open position.

As shown in Figure 1 of the drawing, the small door or the like 5 which is hinged at 6 and 7 to the large door 4 in any suitable manner is preferably spaced a small distance from the bottom edge 4c of the large door 4. This provides the conventional step-over portion of the large door which is generally designated in the drawing by the reference numeral 8 and upon which the improved latching mechanism of the present invention is preferably mounted.

Accordingly, the channel-shaped housing or casing 9 is secured to the step-over portion of the large door in any suitable manner such as by cap screws or the like. The lever or the like 10 which is disposed within the housing 9 is pivotally secured thereto preferably by means of the pin member or the like 11. The arm or the like 12 which is pivotally secured to one extremity of the lever 10 preferably by means of the slot 13 formed therein and the pin member 14 extends downwardly therefrom through the conventional guide or bracket 15 which is secured in any suitable manner to the inner surface of the housing 9. In this way as will be more apparent hereinafter the arm 12 is adapted to slide in a vertical manner within the bracket 15 whereby (depending upon the angular disposition of the pivoted lever 10) the lower extremity of the arm assumes either an extended or a retracted position with respect to the bottom edge of the large door 4.

The arm or the like 16 which is preferably similarly pivotally secured to the opposite extremity of the lever 10 by means of the slot 17 and the pin member 18 extends upwardly therefrom through the guide or bracket member 19 which is secured to the casing 9 in any suitable manner. As will also be more apparent hereinafter depending upon the angular disposition of the lever 10 the arm 16 assumes either an extended or a retracted position with respect to the upper edge of the step-over portion of the large door. Any suitable device such as the elongated tension spring or the like 20 which is preferably secured as shown between the bracket 15 and an upper portion of the arm 12 biases the lever 10 in a clockwise fashion toward a position where both of the arms 12 and 16 normally occupy their extended positions.

In operation the improved latching device which is constructed in accordance with the present invention automatically moves between its latched and its unlatched conditions depending upon the position of the large door 4. Accordingly, when the large door 4 occupies its lowermost and closed position, the floor of the building 3 engages the lower extremity of the arm 12 and urges it upwardly against the bias of the spring 20. This causes the lever 10 to rotate about its pivot in a counterclockwise direction and consequently also moves the arm 16 to its retracted position. In this condition the small door 5 is unlatched and may be opened and closed as desired. When, however, the large door begins to open and move towards its overhead or elevated position, the spring 20 immediately urges the arm 12 downwardly thereby causing the lever 10 to rotate in a clockwise direction and to move the arm 16 upwardly into latching engagement with the bottom portion of the small

door 5. In this way the small door is positively and securely latched in its closed position while the large door is open and the safety of persons working and/or passing therebelow is better assured.

A modified embodiment of the present invention is illustrated in Figure 3 of the drawing. As shown therein, the operative connection between the extendable and retractable arms or the like 31 and 32 includes the complementary toothed rack portions 31a and 32a thereof and the pinion 33 with which the rack portions cooperate. As in the previously described embodiment of the invention one or more tension springs or the like 34 normally bias the arms toward their extended positions.

Although both embodiments of the improved latching mechanism of the present invention have been shown and described herein as being mounted on and housed in a suitable casing which is secured to the step-over portion of the large door, it is to be understood that the same could instead be positioned within a suitably hollowed portion of the door without departing from the spirit or scope of the present invention.

Obviously many modifications and variations of the present invention are possible in the light of the above teachings. It is therefore to be understood that within the scope of the appended claims the invention may be practiced otherwise than as specifically described.

What is claimed is:

1. In combination with a large overhead type of door having a small door disposed therein a device for latching the said small door in its closed condition comprising a first member which is slidably positioned on the large door and which is adapted to retractably extend downwardly beyond the lower extremity thereof; a second member which is also slidably positioned on the large door and which is adapted to retractably extend beyond the jamb of the small door; and means operatively connected to the said first and second members for simultaneously moving them between their extended and retracted positions.

2. In combination with a large overhead type of door having a small door disposed therein a device for latching the said small door in its closed condition comprising a housing mounted on a step-over portion of the large door, the step-over portion being disposed between juxtaposed bottom edges of the said large door and the said small door; a first member which is slidably positioned in the housing and which is adapted to retractably extend downwardly through an opening in the housing and beyond the lower extremity of the large door; a second member which is also slidably positioned in the housing and which is adapted to retractably extend upwardly beyond the lower extremity of the small door; and means operatively connected to the said first and second members for simultaneously moving them between their extended and retracted positions.

3. In combination with a large overhead type of door having a small door disposed therein a device for latching the said small door in its closed condition comprising a first member which is slidably positioned on the large door and which is adapted to retractably extend downwardly beyond the lower extremity thereof; a second member which is also slidably positioned on the large door and which is adapted to retractably extend beyond the jamb of the small door; means operatively connected to the said first and second members for simultaneously moving them between their extended and retracted positions; and means for normally biasing the said first and second members toward their extended positions.

4. In combination with a large overhead type of door having a small door disposed therein a device for latching the said small door in its closed condition comprising a lever which is pivotally positioned on a step-over portion of the large door, the step-over portion being disposed between juxtaposed bottom edges of the said large

door and the said small door; a first member which is pivotally connected to one extremity of the lever and which is adapted to retractably extend downwardly beyond the bottom edge of the large door; a second member which is pivotally connected to the opposite extremity of the lever and which is adapted to retractably extend upwardly beyond the bottom edge of the small door; and means for normally biasing the said first and second members toward their extended positions.

10 5. In combination with a large overhead type of door having a small door disposed therein a device for latching the said small door in its closed condition comprising a lever which is pivotally positioned on a step-over portion of the large door, the step-over portion being disposed between juxtaposed bottom edges of the said large door and the said small door; a first member which is pivotally connected to one extremity of the lever and which is adapted to retractably extend downwardly beyond the bottom edge of the large door; a second member which is pivotally connected to the opposite extremity of the lever and which is adapted to retractably extend upwardly beyond the bottom edge of the small door; and a tension spring which is secured to and extends between the bottom of the large door and an upper portion of the said first member and which normally urges the said first and second members toward their extended positions.

30 6. In combination with a large overhead type of door having a small door disposed therein a device for latching the said small door in its closed condition comprising a lever which is pivotally positioned on a step-over portion of the large door, the step-over portion being disposed between juxtaposed bottom edges of the said large door and the said small door; a bracket member mounted on the step-over portion of the large door; a first arm which is pivotally connected to one extremity of the lever and which is adapted to retractably extend downwardly through the bracket member and beyond the bottom edge 35 of the large door; another bracket member mounted on the step-over portion of the large door; a second arm which is pivotally connected to the opposite extremity of the lever and which is adapted to retractably extend upwardly through the said other bracket member and beyond the bottom edge of the small door; and means for 40 normally biasing the said first and second arms toward their extended positions.

then extended positions.

7. In combination with a large overhead type of door having a small door disposed therein a device for latching the said small door in its closed condition comprising 50 a pinion which is pivotally positioned on a step-over portion of the large door, the step-over portion being disposed between juxtaposed bottom edges of the said large

door and the said small door; a first rack member which is operatively connected to the pinion and which is adapted to retractably extend downwardly beyond the bottom edge of the large door; a second rack member which is also operatively connected to the pinion and which is adapted to retractably extend upwardly beyond the bottom edge of the small door; and means for normally biasing the said first and second rack members toward their extended positions.

65 8. In combination with a large overhead type of door having a small door disposed therein a device for latching the said small door in its closed condition comprising a pinion which is pivotally positioned on a step-over portion of the large door, the step-over portion being disposed between juxtaposed bottom edges of the said large door and the said small door; a first rack member which is operatively connected to the pinion and which is adapted to retractably extend downwardly beyond the bottom edge of the large door; a second rack member which is also operatively connected to the pinion and which is adapted to retractably extend upwardly beyond the bottom edge of the small door; and a tension spring 70 which is secured to and extends between the bottom of 75

the large door and an upper portion of the said first rack member and which normally urges the said first and second rack members toward their extended positions.

9. In combination with a large overhead type of door having a small door disposed therein a device for latching the said small door in its closed condition comprising a pinion which is pivotally positioned on a step-over portion of the large door, the step-over portion being disposed between juxtaposed bottom edges of the said large door and the said small door; a bracket mounted on the step-over portion of the large door; a first rack member which is operatively connected to the pinion and which is adapted to retractably extend downwardly through the bracket and beyond the bottom edge of the large door; another bracket mounted on the step-over portion of the large door; a second rack member which is operatively connected to the pinion and which is adapted to retractably extend upwardly through the said other bracket and beyond the bottom edge of the small door; and means for normally biasing the said first and second rack members toward their extended positions.

10. In combination with a large overhead type of door having a small door disposed therein a device for latching the said small door in its closed condition com-

15 prising a housing mounted on a step-over portion of the large door, the step-over portion being disposed between juxtaposed bottom edges of the said large door and the said small door; a first member which is slidably positioned in the housing and which is adapted to retractably extend downwardly through an opening in the housing and beyond the lower extremity of the large door; a second member which is also slidably positioned in the housing and which is adapted to retractably extend upwardly beyond the lower extremity of the small door; means operatively connected to the said first and second members for simultaneously moving them between their extended and retracted positions; and means for normally biasing the said first and second members toward their extended positions.
